UNITED STATES PATENT OFFICE.

GUILFORD W. HENRY, OF ST. LOUIS, MISSOURI.

FOLDING DAVENPORT.

1,032,543.

Specification of Letters Patent. Patented July 16, 1912.

Application filed October 4, 1911. Serial No. 652,717.

To all whom it may concern:

Be it known that I, GUILFORD W. HENRY, a citizen of the United States, residing at St. Louis, Missouri, have invented a certain new and useful Improvement in Folding Davenports, of which the following is a full, clear, and exact description, such as will enable others skilled in the art to which it appertains to make and use the same.

10 This invention relates to folding davenport and couches of the type shown in my prior United States Patent No. 996,243, dated June 27, 1911.

The main object of my present invention is to provide a folding davenport or couch of the character referred to that comprises means for automatically locking the back in elevated position. And still another object is to provide a couch or davenport of the 20 character described in which the means that releases the back-locking mechanism is hidden from view.

Other objects and desirable features of my invention will be hereinafter pointed out.

25 Figure 1 of the drawings is a front elevational view of a portion of a folding davenport constructed in accordance with my invention; Fig. 2 is an end elevational view of same partly broken away so as to more clearly illustrate the construction of the back of the davenport; Fig. 3 is a similar view showing the back in elevated position; Fig. 4 is a perspective view of a portion of the back and part of the means that guides the 30 back and locks it in position; Figs. 5 and 6 are perspective views illustrating slight modifications of my invention; and Fig. 7 is a perspective view of the means for disengaging the pawls or moving them into 35 an inoperative position so as to release the movable back.

Referring to the drawings which illustrate the preferred form of my invention, A designates the end frames of any preferred design and construction; 1 designates the seat, and 2 designates the back. The mattress-support consists of two sections or frames 3 and 4 arranged in such a manner that they lie close together in the same horizontal plane 50 when the davenport is open, as shown in Fig. 3. The seat 1 rests upon the frame 3, and suitable means, not shown, is provided for permitting the frame 3 to be swung upwardly and outwardly into the position

shown in Fig. 3 and for simultaneously moving the frame 4 upwardly into the same horizontal plane as the frame 3. 55

The back 2 is arranged between the end frames A, and said end frames are provided with tracks which receive laterally projecting devices located at the ends of the back 2 so as to guide said back when it is being raised or lowered. In the preferred form of my invention, as herein shown, each end frame A is provided on its inner side with a track composed of a casting or a pair of bars or plates 5 arranged in an inclined position, as shown in Fig. 2, and spaced away from each other so as to form a groove 6 which receives a projection on the back 2. 60 Said projection may either consist of a roller 7, as shown in Fig. 4, a trunnion 7^a, as shown in Fig. 5, or a pivotally mounted block 7^b, as shown in Fig. 6. Guide links 8 are pivotally connected to the end frames A and to the back 2 adjacent the upper edge of same so as to prevent said back from tilting forwardly or backwardly when the operator raises the back or moves it into its elevated position, as shown in Fig. 3. Said guide 65 links can be pivotally connected to the end frames and to the back in various ways but I prefer to provide the end frames and the back with laterally projecting trunnions 9, as shown in Figs. 2, 3 and 4 which project into holes in the guide links, said guide links being prevented from becoming detached from the back and the end frames by means of cotter keys 10 that pass through said trunnions. 70

In order that the back will remain locked in its elevated position, I have provided it with pivotally mounted pawls or dogs 11 that coöperate with notches 12 in the upper set of the bars 5, the lower ends of the pawls 11 being bifurcated, as shown in Fig. 4, so that they will straddle said bars. Means is also provided for moving said pawls into an inoperative position so as to release the back 2 and permit it to descend to its normal 95 position, and in the form of my invention herein shown said means consists of a rock shaft 13 that extends longitudinally of the back 2 and to which the pawls 11 are securely connected, an operating plunger 14 connected to a crank arm 13^a on said rock 100 shaft for moving the shaft in one direction, and a spring 15 connected to said crank arm 105

and to the back for moving said rock shaft in the opposite direction. The rock shaft 13 extends through the back 2, as shown in Fig. 2, so that it is completely hidden from view, and the spring 15 and plunger 14 are also arranged inside of the back. The only portion of the releasing mechanism which is exposed to view is a head 14^a on the plunger which lies on the front face of the back 2. This head, however, is of the same shape and configuration as the buttons which are used to tuft the davenport, and therefore it does not detract from the appearance of the davenport.

If desired, springs 16 may be used for assisting the operator to move the back upwardly, the springs herein shown being connected to stationary studs on the end frames A and to arms 17 which project downwardly from the lower edge of the back adjacent the ends of the back, as shown in Figs. 2, 3 and 4.

To raise the back the operator simply grasps the back and with the assistance of the spring 16 moves the back upwardly into the position shown in Fig. 3, the tracks 5 causing the back to move rearwardly and the guide links 8 preventing the upper edge of the back from falling forwardly or moving from an approximately vertical position. When the operator releases the back it remains in its elevated position by reason of the pawls or dogs 11 engaging the upper set of notches 12 in the track bars 5. When the operator desires to restore the back to its normal position he tilts the back rearwardly slightly so as to take the weight off the pawls 11, and then grasps the head 14^a on the plunger 14 and pulls said plunger forwardly so as to rock the shaft 13 and thus disengage the pawls from the upper set of notches 12. The back is then free to descend by gravity to its normal position, and the spring 15 restores the rock shaft 13 and pawls 11 to normal position so that said pawls will automatically engage the notches 12 when the back is again raised or elevated. Should the head of the plunger 14 slip from the operator's fingers while the back is moving downwardly the pawls 11 will engage the intermediate set of notches 12 and thus prevent injury to the operator or damage to the davenport.

While I prefer to provide the back with rollers 7 so as to reduce the friction to a minimum, I do not wish it to be understood that rollers are essential, for, if desired, the back could merely be provided with laterally projecting pins or trunnions 7^a, as shown in Fig. 5, or pivotally mounted blocks 7^b, as shown in Fig. 6. Furthermore, while I have herein stated that the tracks which guide the back are preferably formed from plates or bars connected to the end frames of the davenport, it will, of course, be understood that

various other means could be used for guiding the back without departing from the spirit of my invention.

In a davenport of the construction above described the back can be raised and lowered easily, and when it reaches its elevated position it is locked automatically; and when it is desired to restore the back to normal position the operator merely has to tilt the back rearwardly slightly and pull forwardly on the plunger 14 so as to disengage the pawls from their co-operating notches.

Having thus described my invention, what I claim as new and desire to secure by Letters Patent is:

1. A folding davenport or couch provided with a movable back, tracks or guideways which govern the path of movement of the back when it is raised, and guide links pivotally connected to said back for controlling the movement of same.

2. A folding davenport or couch provided with a movable back, means for causing said back to remain in a substantially upright or vertical position when it is moved upwardly, means for automatically locking said back in its elevated position, and means for releasing said back so as to permit it to descend.

3. A folding davenport or couch provided with end frames, a movable back arranged between said end frames, inclined guideways or tracks on said end frames which determine the path of movement of the back when it is raised, links pivotally connected to said end frames and to the back adjacent the upper edge of the back for controlling the movement of said back, and means for retaining the back in its raised position.

4. A folding davenport or couch provided with end frames, a movable back arranged between said end frames, guideways or tracks on said end frames which co-operate with the back, links pivotally connected to said back and end frames for controlling the movement of said back, means for automatically locking said back when it reaches its elevated position, and means under control of the operator for releasing said locking means.

5. A davenport or couch provided with end frames which have notches, a movable back arranged between said end frames and adapted to be moved upwardly, pawls on said back which are adapted to engage the notches on the end frame so as to lock the back in elevated position, and means for disengaging said pawls from said notches.

6. A davenport or couch provided with end frames which have notches, a movable back arranged between said end frames and adapted to be moved upwardly, pawls on said back which are adapted to engage the notches on the end frames so as to lock the back in elevated position, a rock shaft in said back for actuating said pawls, and

means under control of the operator for moving said rock shaft.

7. A folding davenport or couch provided with end frames, a movable back arranged between said end frames, inclined guideways or tracks on said end frames, projections arranged adjacent the lower edge portion of the back that enter said guideways, guide links pivotally connected to the end frames and to said back adjacent the upper edge of the back for controlling the movement of same, and means for assisting the operator to move the back.

8. A folding davenport or couch provided with end frames, a movable back arranged between said end frames, inclined guideways or tracks on said end frames, projections on said back that enter said guideways, guide links pivotally connected to the end frames and to said back for controlling the movement of same, a rock shaft extending longitudinally through said back and provided with means for locking the back in its elevated position, and an operating device for said rock shaft that terminates in the front face of said back.

9. A folding davenport or couch provided with end frames, a movable back arranged

between said end frames, inclined track members on said end frames, projections on said back which coöperate with said track members, guide links pivotally connected to said end frames and back, a rock shaft extending longitudinally through said back and provided with pawls or dogs that coöperate with teeth on said track members, an operating device connected to a crank on said rock shaft for moving said shaft in one direction, and a spring for moving said shaft in the opposite direction.

10. In a folding davenport or couch, a movable back, means for causing said back to move rearwardly and upwardly when it is raised, springs which tend to move the back upwardly, means for automatically locking the back in an elevated position, and means under control of the operator for releasing said locking means.

In testimony whereof I hereunto affix my signature in the presence of two witnesses, this second day of October 1911.

GUILFORD W. HENRY.
